BASE SUPPORT FOR A MEDICAL EXAMINATION TABLE

Terry J. Simpkins, Columbus, Ohio, assignor to Industrial Equipment Company, Minster, Ohio, a corporation of Ohio

Filed Apr. 8, 1968, Ser. No. 11,345

Term of patent 14 years

Int. Cl. D24—02; D6—01
U.S. Cl. D83—1

The side of the base support for a medical examination table not shown is the same as the side shown in FIGURE 1. The broken lines representing the table top is shown for illustrative purposes only.

I claim:

The ornamental design for a base support for a medical examination table, substantially as shown and described.
